UNITED STATES PATENT OFFICE.

THOMAS B. ATTERBURY, OF PITTSBURG, PENNSYLVANIA.

DESIGN FOR A DISH-COVER.

SPECIFICATION forming part of Design No. 19,248, dated August 6, 1889.

Application filed July 2, 1889. Serial No. 316,339. Term of patent 7 years.

To all whom it may concern:

Be it known that I, THOMAS B. ATTERBURY, a citizen of the United States, residing at Pittsburgh, in the county of Allegheny and State of Pennsylvania, have invented and produced a new and original Design for Dish-Covers; and I do hereby declare the following to be a full, clear, and exact description of the same, reference being had to the accompanying drawing, forming a part thereof.

In the accompanying drawing I have shown a dish-cover in perspective and designed in representation of a pyramid of eggs, the handle portion of the cover representing a chicken 15 which has partly broken its way out of its shell.

The main feature of my design is the raised or mound-shaped cover, in the form of a hill of eggs in straw with a chicken breaking 20 through the top egg to form the handle portion.

Referring to the illustration of my design, A indicates the main body, which has arranged in a circle two rows of eggs, the upper row being represented as standing on ends. The 25 handle portion of the cover (indicated by the letter B) represents a chicken picking through the top egg.

What I claim is—

A design for a dish-cover, the same consisting of a pyramid of eggs, the top egg forming the handle portion, representing a chicken as just emerging out of the shell, as herein described and shown.

In testimony whereof I affix my signature in 35 presence of two witnesses.

THOMAS B. ATTERBURY.
